(57) **CLAIM**

The ornamental design for a crawl space access door, as shown and described.

DESCRIPTION

FIG. 1 is a front perspective view of the crawl space access door;

FIG. 2 is a rear perspective view of the crawl space access door;

FIG. 3 is a front elevation view of the crawl space access door;

FIG. 4 is a rear elevation view of the crawl space access door;

FIG. 5 is a bottom plan view of the crawl space access door;

FIG. 6 is a top plan view of the crawl space access door;

FIG. 7 is a right side elevation view of the crawl space access door;

FIG. 8 is a left side elevation view of the crawl space access door;

FIG. 9 is a front perspective view of the crawl space access door with the door panel in a reversed alternative configuration; and,

FIG. 10 is a rear perspective view of the crawl space access door with the door panel in a reversed alternative configuration.

FIG. 11 is a front perspective view of the door panel of the crawl space access door;

FIG. 12 is a front perspective view of the door frame of the crawl space access door;

FIG. 13 is a cross-section view of the crawl space access door taken along line 13-13 in FIG. 3;

FIG. 14 is a cross-section view of the crawl space access door taken along line 14-14 in FIG. 4; and,

FIG. 15 is a front perspective view of the door frame of the crawl space access door.

The broken lines in the drawings depicting the latch and handle form no part of the claimed design.
